UNITED STATES PATENT OFFICE.

JOHN W. BARNETT AND MORTON SANDERS, OF MONMOUTH, ILLINOIS.

MARKING ATTACHMENT FOR CORN-PLANTERS.

No. 801,962.

Specification of Letters Patent.

Patented Oct. 17, 1905.

Application filed June 21, 1905. Serial No. 266,282.

To all whom it may concern:

Be it known that we, JOHN W. BARNETT and MORTON SANDERS, citizens of the United States, residing at Monmouth, in the county of Warren and State of Illinois, have invented a new and useful Marking Attachment for Corn-Planters, of which the following is a specification.

This invention relates to land-markers, such as are used, for instance, in connection with corn-planters for the purpose of laying out or marking the land as the machine progresses for the purpose of guiding the driver or operator upon the return trip; and it has for its object to simplify and improve the construction and operation of this class of devices.

With these and other ends in view, which will readily appear as the nature of the invention is better understood, the invention consists in the improved construction and novel arrangement and combination of parts, which will be hereinafter fully described, and particularly pointed out in the claim.

In the accompanying drawings has been illustrated a simple and preferred form of the invention, it being, however, understood that no limitation is necessarily made to the precise structural details therein exhibited, but that alterations and modifications may be made within the scope of the invention.

In said drawings, Figure 1 is a sectional elevation of the corn-planter equipped with the invention. Fig. 2 is a rear elevation of the same. Fig. 3 is a perspective detail view, enlarged, illustrating the means for connecting the marker-staff with the frame of the machine; and Fig. 4 is a perspective detail view of the arch-bar, which constitutes a part of the invention.

Corresponding parts in the several figures are indicated throughout by similar characters of reference.

The main frame or wheel-frame 1 of an ordinary corn-planter has been shown as being provided upon the sides thereof with bracket members 2, supporting at their lower ends the shaft or axle 3 and at their upper ends a transverse shaft 4. Fulcrumed upon the latter is a hand-lever 5, having a forward-extending arm 6 and a rearward-extending arm 7. The front ends of the side members of the wheel-frame are connected pivotally or hingedly in the usual manner with the front or runner frame 7, which supports the seed-boxes 8 and is provided with a tongue 9, the

rear end of which has a perforated bracket 10, through which extends a curved rod 11, the upper end of which is pivotally connected with the arm 6 of the lever 5 and the lower end of 60 which is provided with a tightening-nut 12 for the purpose of regulating the tension of a spring 13, which is coiled upon the rod 11 and exerts pressure in a downward direction upon the bracket 10 at the rear end of the frame 65 for the purpose of elevating the front end of the latter and taking weight off the necks of the draft-animals and also assisting in the adjustment of the runner-frame when the latter is to be raised at the ends of the rows. 70

The operator's or driver's seat 14 is supported upon a tripod, two members of which, 15, are connected with the side members of the wheel-frame, the third member being extended forwardly and connected with the shaft 75 4, upon which the hand-lever is fulcrumed. The seat-supporting member 16 has a quadrant 17 attached thereto for engagement with a stop member 18, connected with the hand-lever 5, which latter may be thereby retained at various adjustments. 80

The seat-supporting members 15 are connected by a cross bar or brace 19, through which extends a supporting-rod 20, the front end of which is firmly connected with the 85 seat-supporting member 16 and the rear end of which terminates in a hook 21, supporting a pulley 22. A pulley 23 is supported for rotation in the rear end of the lever-arm 7, which is bifurcated for the reception of said 90 pulley, together with a cross-pin 24, which serves to prevent the flexible member, which is guided over the pulley 23, as will be presently described, from slipping out of engagement with said pulley. 95

Upon the side members of the wheel-frame 1, near the rear end of the latter, is supported a cross-bar 25, which is connected with said side members by means of hook-bolts 26 and nuts 27. The cross-bar 25 carries an approximately semicircular arch-bar 28, which may be constructed of round iron, the ends thereof being firmly attached to the cross-bar 25. The rear cross-bar 29 of the frame 1 has been shown as provided with a reinforcing-plate 100 30, an aperture 31 being provided in said cross-bar and reinforcing-plate for the passage of a stud 32, having a reduced threaded end 33 for the reception of a nut 34, whereby said stud is mounted in the rear cross-bar 29 105 32 in such a manner as to be capable of rotating freely. The stud 32 has a head 35, which is 110

provided with a slot 36, in which is pivoted the marker-staff 37, which latter is provided at its outer end with a ground-engaging shoe 38, which may be of circular form, as shown 5 in the drawings, although any suitable form of shoe will answer the purposes of the invention. Suitably connected with the fixed point of the marker-staff is one end of a chain 39, the other end of which has a ring 10 or link 40 loosely engaging the arch-bar 28. Likewise connected with the marker-staff at or near the point of attachment of the chain 39 is one end of a flexible member 41, which is guided over the pulleys 22 and 23, the free 15 end of said flexible element being attached to the rod 20 near the front end of the latter or to any other suitable fixed point. It is obvious that the flexible member 41 is to be of such a length that it may serve to support 20 the marker in ground-engaging position when the corn-planter with which it is connected is traversing the field.

When the machine is to be turned at the end of the row, the hand-lever is manipulated to 25 elevate the rear end of the tongue, together with the runner-frame, thus depressing the rearward-extending arm 7 and manipulating the flexible element 41 so as to elevate the marker-staff to the position shown in dotted 30 lines in Fig. 1, thus enabling the machine to be turned and placed in position for the return trip, when by again manipulating the hand-lever 5 the tongue and the runner-frame will be restored to operative position. The 35 same will be the case with the marker-staff, provided that the first operation of the lever 5 was accomplished with sufficient force to swing the marker-staff across its pivotal center; if not, it may be found necessary for the 40 operator to move it slightly by hand in order to cause it to descend at the proper side of the machine. The chain member 39 by engaging the arch-bar 28 not only serves to guide the marker-staff with relation to said arch-bar, 45 but its length may also be so adjusted as to

support the marker-staff in operative position, thus at all times relieving the flexible element 41 of the strain caused by the weight of said bar.

The marker-staff 37 being connected pivotally with the supporting-pivot 32 at an angle 50 to the axis of the latter will at all times swing clear of the driver's seat, its movement with relation to the planter-frame being practically of a universal character.

This invention, as will be seen from the foregoing description, is simple in its nature, and it may be easily and effectively applied to check-row corn-planters of ordinary construction.

Having thus described the invention, what 60 is claimed is—

A planter-frame, a seat-supporting tripod upon said frame, a cross-bar connecting two of the seat-supporting members, a bracket connected with the third seat-supporting member 65 and extending rearwardly through said cross-bar, a quadrant securely connected with one of the seat-supporting members, a hand-lever supported concentric with said quadrant and having a stop engaging the latter and a 70 rearward-extending arm, a marker-staff connected pivotally with the planter-frame, a pulley supported at the free end of the bracket member, a flexible member connected with the marker-staff and guided over said pulley to a 75 fixed point of attachment, and a guide-pulley connected with the rearward-extending arm of the hand-lever and engaging said flexible element intermediate the guide-pulley at the free end of the bracket and the fixed point of attachment.

In testimony that we claim the foregoing as our own we have hereto affixed our signatures in the presence of two witnesses.

JOHN W. BARNETT.
MORTON SANDERS.
